UNITED STATES PATENT OFFICE.

JOSEPH G. PERKINS, OF CINCINNATI, OHIO.

BATH SHOWER ATTACHMENT.

1,165,705.

Specification of Letters Patent. Patented Dec. 28, 1915.

Application filed September 13, 1915. Serial No. 50,506.

To all whom it may concern:

Be it known that I, JOSEPH G. PERKINS, a citizen of the United States, residing at Cincinnati, in the county of Hamilton and State of Ohio, have invented certain new and useful Improvements in Bath Shower Attachments, of which the following is a specification.

My invention relates to improvements in shower attachment for baths.

10 One of its objects is to provide a new and simple combination of elements capable of attachment to any bath tub and readily and conveniently operable.

15 Another object is to provide a shower which is effective as to the place where the shower is delivered and which is not liable to throw water outside of the tub and which does not require a curtain.

20 My invention also comprises certain details of form, combination and arrangement, all of which will be fully set forth in the description of the accompanying drawings, in which:

25 Figure 1 is a vertical section through a bath tub illustrating my improvements in side elevation. Fig. 2 is an enlarged front elevation of the hot and cold water cocks and a portion of my improved shower attached thereto. Fig. 3 is an enlarged sectional view on line Z Z of Fig. 2.

The accompanying drawings represent the preferred embodiment of my invention in which—

35 A represents a bath tub.

B and C represents the hot and cold water cocks, and D the exit port leading therefrom to the tub.

My improved shower attachment comprises a cock or valve E seated in a shell F which has an exit port or tube f leading therefrom to the tub and a socket G to detachably seat over the the exit port D. Attached to the end of the valve E are two elbows g and h to form a double bend from which a line of metal tubing H projects forward of the cocks B and C. A series of rose head spraying nozzles J are connected at intervals to the tube H. If desired each of said nozzles J may be attached by means of adjustable sockets or couplings to the tube H so as to be adjustable angularly in a plane with the longitudinal center of the tube to throw the shower chiefly to any desired portion of the tub or to adjust the shower to cover the interior of a long or

short tub. Ordinarily however, the two lower nozzles J are rigidly mounted with reference to the tube H, and only the nozzle at the outer end of the tube H is adjustable to cause the shower to accommodate itself to or within the dimensions of the tub. The valve E has a rotary movement within its casing of approximately ninety degrees and when the tube H stands in a substantially vertical position as in full line Fig. 1, the water flows through the recess e of the valve E and out through the port f to the tub. In this position the temperature of the water may be adjusted or the tub filled, and the water is positively cut off from the shower.

When the shower is to be employed the tube H is pulled over to the inclined position indicated in dotted line Fig. 1, and the valve E assumes the position shown in Fig. 3 cutting off the water supply through the passage e and causing the water to enter the passage d and flow therefrom through the elbows g and h and tube H to the nozzles J, which are in position to direct the shower onto a person in the tub, and without discharging any water outside of the tub. As soon as the tube H is restored to vertical position the water supply thereto is positively cut off therefrom, and said tube and nozzles are out of the way and permit uninterrupted use of the tub.

In order to detachably secure the shower attachment to any tub I provide a clamping fork or yoke K having a screw L and a platen M. A rubber washer n is placed in the socket G and the hooked ends of the yoke K engage under the outside of the socket, after which the screw L and platen M serve to firmly clamp the socket G over the end of the exit port D.

A pin b projecting from the valve E engages a segmental recess in the casing F to limit the movement of valve E and tube H. Tube H is preferably set to stand as illustrated in Fig. 1, but may be set at a different angle if desired. The tube H is preferably arranged to be detached into short sections for shipping and storage. The exit port f is designed if desired to receive a flexible rubber tube carrying a rose head spraying nozzle to spray the hair or head.

The mechanism herein illustrated and described is capable of considerable modification without departing from the principle of my invention.

Having described my invention, what I claim is:

1. A bath shower attachment comprising a valve casing having a downwardly directed exit port and an upwardly directed coupling member to couple it to a source of water supply, a two-way valve seated in said casing, a shower tube connected to said valve and provided with a plurality of spray nozzles, said shower tube being movable with said valve from a substantially vertical position to an inclined position over a bath tub, said valve having one passage to lead water to the exit port of said casing and another passage to conduct water to said shower tube and nozzles.

2. A bath shower attachment comprising a valve casing having an exit port to a tub a two-way valve seated in said casing and carrying a shower tube movable with said valve as a center from a substantially vertical to an inclined position over a tub, said valve serving to positively direct water either through the exit port of said casing to a tub or through said shower tube to a tub.

3. A detachable bath shower attachment comprising a valve casing having an exit port to a tub means to detachably connect said casing to the water exit of a tub, a two-way valve having a passage to direct water to the exit port of said casing and a pas-

sage to direct water out through one end of said valve, and a tube connected to said last named passage and movable with said valve from a substantially vertical position out of the way to an inclined operative position over a bath tub, and serving as a handle to operate said valve, said tube being provided with perforations to direct a shower downwardly into the tub when said valve is in position to supply water to said tube.

4. A bath shower attachment comprising a valve casing having a downwardly directed exit port and an upwardly directed coupling member to couple it to a source of water supply, a two-way valve seated in said casing, a shower tube connected to and movable with said valve from a substantially vertical position when inoperative to an inclined position over a bath tub when in operative position and provided with one or more rigid spray nozzles and at its outer end with an adjustable spray nozzle, said valve having one passage to positively lead water to the exit port of said casing and another passage to conduct water to said shower tube and nozzles.

In testimony whereof I have affixed my signature in the presence of two witnesses.

JOSEPH G. PERKINS.
